FOOTBALL HELMET CUP FOR COMESTIBLES OR THE LIKE

George Dickstein, Shaker Heights, and David A. Shack,
Beachwood, Ohio, assignors to Sports Products Corporation,
Cleveland, Ohio

Filed Oct. 30, 1973, Ser. No. 411,058

Term of patent 14 years

Int. Cl. D7—01

U.S. Cl. D7—5

Fig. 1

Fig. 2

Fig. 3

Fig. 4

*Fig. 5**Fig. 6*FIG. 1 is a three-quarter perspective view of a football helmet cup for comestibles or the like showing our new design in an inverted condition;

FIG. 2 is a front elevational view thereof;

FIG. 3 is a side elevational view thereof;

FIG. 4 is a three-quarter perspective view thereof showing our new design in its position of use;

FIG. 5 is a three-quarter perspective view showing another embodiment of our new design in an inverted condition; and

FIG. 6 is a plan view thereof showing the embodiment of our new design in its position of use.

We claim:

The ornamental design for a football helmet cup for comestibles or the like, substantially as shown and described.
